(57) **CLAIM**

The ornamental design for an optical semiconductor device, as shown and described.

DESCRIPTION

FIG. 1 is a front, top and left side perspective view of an optical semiconductor device, showing my new design;

FIG. 2 is a top plan view thereof;

FIG. 3 is a front elevational view thereof;

FIG. 4 is a right side elevational view thereof; the opposite side being a mirror image thereof;

FIG. 5 is a rear elevational view thereof; and,

FIG. 6 is a bottom plan view thereof.
